UNITED STATES PATENT OFFICE.

JOHN WHITEHEAD, OF MANCHESTER, ENGLAND.

WINDOW SASH AND WINDOW FRAME.

1,412,640.

Specification of Letters Patent. Patented Apr. 11, 1922.

Application filed May 20, 1920. Serial No. 382,934.

To all whom it may concern:

Be it known that I, JOHN WHITEHEAD, a subject of the King of Great Britain and Ireland, residing at 401 Greymare Lane, 5 Bradford, Manchester, England, have invented new and useful Improvements in Window Sashes and Window Frames, of which the following is a specification.

This invention relates to windows of the kind in which the sashes are adapted to slide up and down for opening and closing purposes but can be swung inwards to allow both sides of the glass being cleaned from the inside of the room or building, and has 15 for its object to provide an improved constructional form and combination of sash and frame.

The invention will be more particularly described by the aid of the accompanying 20 drawings wherein,

Fig. 1 is a front elevation of a window frame with sashes showing the invention applied.

Fig. 2 is a sectional side view showing the 25 bottom sash turned inwards.

Fig. 3 is a sectional plan view on the line 3-3 of Fig. 1.

Fig. 4 is a view corresponding to Fig. 2 but with both sashes turned.

30 Fig. 5 is a sectional elevation of one side of a window frame showing a modified form of parting beading.

Fig. 6 shows the trunnion plate in front, side and plan view.

35 Fig. 7 is a front elevation of a modified form of trunnion and Fig. 8 is a side view of Fig. 7, while

Fig. 9 is a view corresponding to Fig. 2, but with the hinged members folded inwards 40 but with the sashes in normal position.

According to the invention the sashes, *a*, *b* (upper and lower respectively) are made of the conventional or other convenient form but on each side and about midway in their 45 length each sash is provided with a short trunnion *c* preferably carried by a metal plate *d* let into the wood and formed with a flange *d'* on one side to receive screws or other securing means.

50 Said flange *d'* in practice is preferably arranged to normally lie on the outside edge of the window sash and the arrangement is such that when the securing means are released the sash can be bodily removed by 55 tilting the same clear of the trunnion plate *d*.

The trunnion *c* on the opposite side of the sash may be a fixture and where the proportions of the window are such as to allow the trunnions to leave the grooves in the frame, hereinafter explained, the trunnions on both 60 sides may be fixtures as illustrated in Figs. 7 and 8.

The trunnions *c* of the outside sash *a* slide in grooves *e* formed in the usual vertical runways of the window frame *f*, said grooves 65 extending from the sash cord pulley *g* to within a short distance above the normal position of the trunnions on the bottom sash. The usual outer and inner beading *h* and *i* and parting stripping *i'* respectively are provided to form additional guides for said sashes *a* and *b* the outside beading *h* descending almost to the bottom of the groove *l* while the inner or middle beading *i'* is shorter, i. e. lower part is removable, to allow 75 the sash *a* to be swung inwards on its trunnions as seen in Fig. 4.

The upper sash *a* is provided at each side with a strip *i''* normally aligned with and substantially forming an extension of the 80 adjacent parting strip *i'*.

To the outside of the window frame at the bottom thereof, and one on each side are two strips of wood *t* hinged to the frame adapted to be swung into the position shown in Fig. 85 3 so that the inner edges *t'* complete the grooves in which the inner sash *b* slides and the top end constitutes a stop to limit the downward movement of the top sash *a*. The inner edges *t'* of the strip *t* lie in the grooves 90 formed in the sash *b* to accommodate the inner or parting beads *i'*.

Alternatively the inner or parting bead *i''* may be pivotally connected to the window framing at *i'''* as seen in Fig. 5 so that it can 95 be moved out of the path of the swinging sashes as indicated in dotted lines.

The sash cord *j* is attached to the trunnion *c* and lies within the before-mentioned groove *e*, the pulley *g* being arranged to 100 suit.

The inner sash *b* is also provided with trunnions *c* which slide in grooves *h* parallel to the first set *e* but extend from the respective sash cord pulley *l* to the lowermost 105 position to which the trunnions descend. A recess *m* is formed in the frame into which the bottom edge of the sash sinks, to position it when closed, and hinged rails *n* or beading which form continuations of the bead- 110

ing *i* are provided at each side of the frame to form, in conjunction with the grooves *k*, guides to retain the sash *b* in the correct path, while being raised or lowered. Said hinged rails *n* also serve as draught preventers and in this respect they may be recessed into the frame or formed as corner pieces.

In Figs. 7 and 8 the trunnion plates *d* 10 are dispensed with, the trunnions being each in the form of a screw *p* surrounded by a sleeve *q* formed with an extension *r* to which the sash cord is attached by means of the hooks *s*.

15 It will now be seen that the sashes can be raised and lowered in the usual manner and when it is desired to swing the sashes inwards to allow access to the exterior of the glass the bottom sash *b* is first raised 20 and the strips *t* turned outwardly as indicated in dotted lines in Fig. 3, and the sash is then lowered to a position just clear of the recess *m*. Upon the hinged rails *n* being turned outwardly the bottom sash *b* 25 can be swung about the trunnions to the position shown in Fig. 2 with the outside of the pane on top in a convenient position for cleaning. It is then returned into position in line with the grooves and the top 30 sash *a* lowered until the trunnions come to rest at the end of the grooves *e*. Both sashes are then turned to the position shown in Fig. 4, the outside of the window pane of the top sash then being uppermost and in 35 the cleaning position.

To return the sashes to the normal position they are swung back into line with the respective slide ways. The hinged beads *n* are then turned back into position and both

sashes raised to the top of the window 40 frame. The outer strips *t* are then turned into position across the inside of the frame and the bottom sash *b* lowered and the window fastened by the catch *o* in the usual manner. When it is desired to have the top 45 sash part open it is lowered on to the strips *t* which form a convenient stop.

In the case of the pivotally mounted parting bead *i* the bottom sash is raised and said bead pushed in when it is desired to 50 turn the sashes inwards.

What I claim is:—

A window of the kind referred to comprising sashes adapted to slide up and down for opening and closing purposes, and a 55 trunnion located substantially midway along the length of each sash and on each side of the same, in combination with a window frame having grooves to receive the trunnions, the lower end of said grooves constituting abutments about which the sashes pivot, the outside grooves being shorter than the inside groove so that both sashes can be 60 swung inwards, and sash cords connected to the sashes about the pivot centres, the inner, outer and parting beadings of the frame being formed with gaps to allow the sashes to swivel, the gap in the inner beading being closed by a hinged section, together 65 with hinged members at the rear of said window frame each adapted to form one 70 side of a guiding groove for the lower sash and a stop for the top sash, substantially as described.

In testimony whereof I have signed my 75 name to this specification.

JOHN WHITEHEAD,
